(57) **CLAIM**

The ornamental design for a hand truck, as shown and described.

DESCRIPTION

FIG. 1 is a perspective view of a hand truck according to an embodiment of the present design in a first orientation with a handle, a pair of wheels, a pair of castors, a plurality of ribs, various openings, and various fasteners shown in broken lines.

FIG. 2 is a front elevation view of the hand truck of FIG. 1.

FIG. 3 is a rear elevation view of the hand truck of FIG. 1.

FIG. 4 is a left side elevation view of the hand truck of FIG. 1.

FIG. 5 is a right side elevation view of the hand truck of FIG. 1.

FIG. 6 is a top plan view of the hand truck of FIG. 1.

FIG. 7 is a bottom plan view of the hand truck of FIG. 1.

FIG. 8 is a perspective view of the hand truck of FIG. 1 in a second orientation with a handle, a pair of wheels, a pair of castors, a plurality of ribs, various openings, and various fasteners shown in broken lines.

FIG. 9 is a front elevation view of the hand truck of FIG. 8.

FIG. 10 is a rear elevation view of the hand truck of FIG. 8.

FIG. 11 is a left side elevation view of the hand truck of FIG. 8.

FIG. 12 is a right side elevation view of the hand truck of FIG. 8.

FIG. 13 is a top plan view of the hand truck of FIG. 8; and, FIG. 14 is a bottom plan view of the hand truck of FIG. 8.

The broken lines shown in FIGS. 1 through 14 illustrate portions of the hand truck that form no part of the claimed design.
